UNITED STATES PATENT OFFICE.

CHARLES T. WILT AND ELMER E. WILT, OF CHICAGO, ILLINOIS, ASSIGNORS TO CHAS. T. WILT,
OF CHICAGO, ILLINOIS, A FIRM.

TRUNK.

No. 880,058.

Specification of Letters Patent.

Patented Feb. 25, 1908.

Application filed August 10, 1906. Serial No. 329,993.

To all whom it may concern:

Be it known that we, CHARLES T. WILT and ELMER E. WILT, citizens of the United States, of Chicago, in the county of Cook 5 and State of Illinois, have invented certain new and useful Improvements in Trunks; and we do hereby declare that the following is a full, clear, and exact description thereof, reference being had to the accompanying 10 drawings, and to the letters of reference marked thereon, which form a part of this specification.

This invention relates to wardrobes, closets or other compartments, such for example 15 as so called wardrobe trunks, wherein garments such as coats, trousers and the like are contained in a hanging or suspended position.

While the invention is applicable alike to many uses such as portable or stationary 20 closets or wardrobes, trunks, lockers and the like, we have, for the sake of convenience merely, illustrated our invention as embodied in a trunk of the type known as wardrobe trunks.

25 The object of our invention is to improve such a compartment in a manner to provide ready means for withdrawing the suspended articles of apparel from the said compartment without disturbing the suspended relation thereof; to provide means for suspending said articles, when withdrawn from said compartment, so that they are ready of access from all sides thereof; to improve and strengthen the devices for supporting the 30 articles of apparel both when contained within the compartment and when withdrawn therefrom, and to produce an extension supporting device for the articles of apparel which may be readily collapsed and folded in 35 the compartment in which the articles are suspended.

The invention consists in the matters hereinafter set forth and more particularly pointed out in the appended claims.

45 In the drawings:—Figure 1 is a perspective view of a wardrobe trunk embodying our invention, showing the trunk open and the suspended articles of apparel contained therein. Fig. 2 illustrates the upper end of 50 the compartment for receiving the suspended articles of apparel, showing the supporting rail and hangers for such articles. Fig. 3 illustrates the manner of supporting the suspended articles outside of said compartment. 55 Fig. 4 is an enlarged cross-section, taken on

line 4—4 of Fig. 2, showing the construction of the carriage on which apparel hangers are supported and by which they may be withdrawn from the trunk compartment. Fig. 5 illustrates the joint between the stationary 60 supporting rail for the apparel hangers and the hinged extension rail, showing portions of the trunk to which said parts are attached. Fig. 6 illustrates said parts in longitudinal section and also illustrating a portion of the 65 hanger carriage in section. Fig. 7 is a bottom plan view of said parts as viewed from the position indicated by the arrows 7—7 of Fig. 5. Fig. 8 is a transverse section, taken on line 8—8 of Fig. 5. Fig. 9 is a side view 70 of the joint between the fixed and hinged portions of the rail, illustrating the hinged portion in its inoperative position. Fig. 10 is a front elevation of the parts shown in Fig. 9. Fig. 11 illustrates the jointed connection between the rail extension and the hinged supporting standard therefor. Fig. 12 is an axial section of the parts shown in Fig. 11. Fig. 13 is a cross-section, taken on line 13—13 75 of Fig. 11. Fig. 14 is a perspective view of 80 a ring, constituting a stop for the telescopic standard. Fig. 15 is an axial section of the rail extension and its telescopic standard, showing the latter occupying a position partially within the hollow extension rail. Fig. 85 16 is an underside view, as shown from the position indicated by the arrows 16—16 of Fig. 15. Fig. 17 is a perspective view of the extension rail detached from the other parts. Fig. 18 is a perspective view of the lower end 90 of the standard for said rail extension and the supporting base or foot therefor.

As shown in the drawings, the trunk comprises two general compartments or halves A and B, hinged together to close one on the 95 other. One of said compartments is fitted with a plurality of drawers A¹ which, when the trunk is setting upon end and open, are available for access thereto. The other compartment has a large free space designed 100 to receive articles of apparel suspended from suitable hangers, and concerning which latter parts certain of our improvements relate. The said hangers and supporting rail therefor are constructed and arranged to be 105 contained entirely within the compartment B when the articles of apparel are suspended therein, and said compartment is adapted to be closed by a door B¹ hinged to one side thereof as shown in Fig. 1. The garment 110

support is designed to be withdrawn from the compartment B to suspend the garments in a position where free access may be had thereto.

5 An apparel support embodying our invention embraces, in general terms, a fixed rail C located within the top of the compartment B of the trunk and extending from front to rear thereof and designed to support a suitable carriage designated as a whole by C¹ which carries a plurality of hangers C²; and an extension rail D that is adapted to be extended horizontally from the fixed rail to support the carriage and hangers, as indicated in dotted lines in Fig. 3, and so constructed that when not in use, it may be contained wholly within the compartment B as indicated in Fig. 1. The said extension rail is supported at its outer end by a 10 standard E that is hinged at its upper end to the outer end of the rail extension D and is provided at its lower end with a suitable base or foot E¹ which rests on the floor when the extension is withdrawn, and is supported 15 on the lower wall of the compartment B of the trunk when the extension is folded within the compartment. Said base or foot of the standard is provided with laterally extending arms e e that afford lateral stability 20 to the base. The said fixed and extension rails are, in the present instance, shown as made hollow and the supporting standard E of the extension rail is adapted to fit in telescopic relation within the hollow extension 25 rail at a time when the device is not in use, whereby the said standard and extension may be contained within practically the vertical space occupied by the extension alone 30 when the latter is swung downwardly about its hinge D¹.

Certain features of the construction involved in the fixed supporting rail and its extension and the carriage for the garment hangers embody portions of our invention. 45 Such features of construction are shown in detail in Figs. 1 to 10, inclusive, and will now be described. The said fixed horizontal section of the rail is mounted at its ends in brackets c c¹ attached to the top wall of the 50 compartment B at the front and rear sides thereof. The extension rail D is hinged to the forward bracket c¹ by being provided at its inner end with laterally separated lugs or ears d d which are pivotally connected 55 with the brackets by means of hinge studs d¹. The said joint is strengthened, when the extension rail occupies its horizontal position, by means of a locking stud d² that extends through registering openings in one 60 of the jaws or ears d¹ and in the bracket.

The fixed and extension rails are so constructed that the hanger carriage, which is supported on the fixed rail when the trunk is closed, is adapted to be shifted outwardly 65 on the extension rail, as shown in Fig. 3

without detaching the carriage or disarranging the suspended positions of the garments on the hangers. The hinged joint between said rails is of special construction to permit of this operation. As herein 70 shown, said rails are tubular and are provided on their lower sides with aligned longitudinal slots d³ d⁴ and the bracket c¹ is provided with a slot c² connecting the slots of the rails. The carriage is provided with 75 front end rear suspending brackets c³ that extend through said slots d³ d⁴ into the tubular rails, and said brackets are preferably provided with roller bearings to facilitate the movement of the carriage along the supporting 80 rails.

The carriage herein shown comprises an elongated loop c⁴ which is swung from the lower ends of the hanging brackets c³ and on the lower member of which are suspended 85 the hangers C². The bearings for said carriage within the tubular, slotted rails consist of axles c⁵ mounted in transverse openings in the hanging brackets c³ and provided at their ends with wheels c⁶ c⁶ engaging the interior 90 surface of the tube. Preferably the wheels c⁶ are made of vulcanized fiber or like non-resonant material, whereby movement of the carriage inwardly and outwardly on the rail produces no objectionable noise. The said 95 wheels are beveled on their peripheries to correspond to the cylindric inner surface of the tube, as shown in Fig. 4, thereby providing ample bearing between said wheels and the tubular rail. The openings in said 100 hanger brackets which receive the axles c⁵ are formed and arranged to provide seats for anti-friction spherical rollers c⁷ which facilitate the rotation of said axles in their bearings.

105 Referring now to the hinged connection of the standard E with the outer end of the extension rail D, and the telescopic connection thereof with said rail, whereby said standard may be forced backwardly into the interior 110 of the rail extension for the purpose stated, said parts are made as follows: The said standard may be and is preferably made of a section of tube of proper length, and is provided at its upper end with a plug e¹ formed to provide one lug or ear of the hinged connection. Located within the tubular, slotted rail extension and having sliding engagement therewith, is a block F that is provided with laterally separated lugs or ears f f which 115 fit outside of the hinge lug e² and are connected therewith by a pivot pin f¹. The complete withdrawal of said sliding block F from the tubular rail extension is prevented by means 120 of a stop located at the outer end of said extension rail, having the form, as herein shown, of a ring G that is riveted or otherwise suitably fixed in said hollow rail extension. The sliding block F, on which is 125 formed a part of the hinge-connection be- 130

tween the supporting standard and rail extension, is provided with a downwardly directed lug f^2 which engages the slot d^4 of said rail extension and prevents rotation of the block 5 and the hinge connected standard relative to said rail extension. The stop ring G is shown as provided on its inner margin, in line with said lug f^2 with a notch g designed to receive said lug f^2 when the standard is at the 10 outer limit of its movement and is swung downwardly in position to support the rail extension. The parts are so disposed at the time when the lug f^2 so occupies said notch g and the standard is swung downwardly at 15 right angles to the rail extension, that the plug e^1 at the upper end of said standard bears closely against the end of the ring and rail extension so as to produce a firm and reliable joint at this place and safely support 20 the weight of the garments supported on said rail.

Inasmuch as the surface upon which the base or foot E^1 of the standard rests when the rail is extended into its outermost position 25 and supported by the standard E , is lower than the bottom wall of the compartment B , it is desirable to make the foot E^1 vertically adjustable relatively to the standard E . As herein shown, this is accomplished by making 30 the foot separate from the standard and providing it with a shank E^2 that extends upwardly through the lower end of the hollow standard. The shank of said foot is connected with the standard by means of a radially disposed pin e^3 on the standard that engages a bayonet notch e^4 formed at one side of a longitudinal slot e^5 in said tubular standard. Said bayonet notch e^4 is located at such 35 distance from the end of the standard as to raise the latter the required distance when the pin is engaged therewith to hold the rail extension horizontal. When the pin e^3 of the shank E^2 is turned into line with the slot e^5 of said hollow standard, the standard may 40 drop with its lower end engaged with the foot E^1 , so that when the standard is telescoped 45 into the hollow rail extension and the latter swung down into the position shown in Fig. 1 the parts may pass readily into the compartment. 50

An important feature of the construction described is the continuous track or runway 55 for the carriage, formed in this instance by the slots in the fixed and extension rails and the hinge joint thereof, whereby the carriage and the suspended hangers may be moved outwardly and inwardly without disconnecting the hanger from the rail or disarranging the garments suspended on the hangers. 60 Another important feature of the construction described, is the construction of the extension rail and the standard therefor described, as it permits the rail to be made of such length that the articles of wearing apparel suspended on the hangers may be with- 65

drawn sufficiently far away from the trunk to permit of a person having access to all sides of a group of garments suspended therefrom, while permitting the rail extension and the standard to be contained wholly 70 within the compartment when not in use. Other important features of construction, which contribute to the ease and certainty of action of the device is the manner of mounting the carriage on the supporting rail and 75 extension, the character of the roller bearing for the carriage and the adjustable arrangement of the foot or base of the standard E .

The construction of the parts is such as to provide an amply strong and rigid connection 80 of the relatively movable parts which promotes the durability and strength of the device.

I claim as my invention:—

1. The combination with a receiving compartment provided with a door, of a tubular, slotted rail fixed to the upper wall of said compartment, a tubular, slotted extension rail hinged or pivotally connected to the fixed rail by a part supported on said upper 85 wall and independent of said door, and a hanger suspending carriage provided with parts which extend through the slots of said rails and have bearing within the hollow rails, the slots of the rails extending continuously from the stationary to the extension rail, when the latter is in operative position, to form a continuous track for said carriage.

2. The combination with a receiving compartment, of a fixed rail therein, a hanger suspending carriage movably mounted thereon, and a rail extension hinged directly to the fixed rail and designed to be folded in said compartment when not in use, said fixed 100 and extension rails being formed to provide a continuous way for the carriage whereby the latter may be moved directly from the fixed rail to the extension rail and vice versa.

3. The combination with a receiving compartment, of a fixed, horizontal rail therein, an extension rail, a hinge directly connecting the latter rail with the fixed rail, and a hanger sustaining carriage movable on said rails, the rails and hinge being arranged to constitute 105 a continuous way for the carriage to permit it to be moved from one rail to the other.

4. The combination with a receiving compartment provided with a laterally swinging door for closing the same, of a stationary rail 110 fixed to the upper wall of the compartment, an extension rail hinged to the stationary rail by a part independent of said door and which is supported on said upper wall of the compartment, means for supporting the extension rail in horizontal alinement with the stationary rail, tracks or ways on said rails arranged to constitute a continuous track 115 from the stationary to the extension rail when the latter occupies its horizontal posi- 120 125 130

tion, and a carriage movable on said tracks or ways.

5. The combination with a receiving compartment, of a tubular, slotted rail fixed horizontally in the upper part of the compartment, a slotted, tubular extension rail, a hinge member on the fixed rail to which the extension rail is pivotally connected, the slots of said rails being located in alinement 10 with each other when the extension rail occupies a horizontal position, the hinge member being provided with a slot disposed in alinement with and connecting the slots of said rails, and a carriage having bearing in 15 the tubular rail and provided with a bracket adapted to travel in said slots.

6. In a wardrobe or receiving compartment, the combination with a fixed horizontal tubular rail therein, of a tubular extension rail hinged thereto and adapted to be folded in the compartment when not in use and when extended for use to occupy a horizontal position in alinement with the fixed rail, said rails being provided in their lower 25 sides with slots disposed in alinement when the extension rail occupies a horizontal position, the hinge of the extension rail being provided with a slot disposed in alinement with and connecting the slots of said rails, and a hanger-sustaining carriage provided 30 with parts extending through said slots and provided within the rails with wheels which rest and roll on track surfaces constituted by the inner walls of the tubular rails.

35. 7. In a wardrobe or compartment, the combination with a fixed horizontal tubular rail, of a tubular extension rail hinged to the fixed rail and adapted to be folded in the said compartment when not in use and to occupy a horizontal position in alinement with the fixed rail when extended for use, said rails being provided in their lower sides with slots which are in alinement when the extension rail occupies the horizontal position, the hinge 40 of the extension rail being provided with a slot in alinement with and connecting the said rail slots, and a hanger-sustaining carriage provided with parts extending through said slots and provided within the rails with 45 wheels which rest and roll on the track surfaces constituted by the inner walls of the tubular rails, said wheels being beveled on their peripheries to engage the inner cylindric walls of the tubular rail.

55. 8. In a wardrobe or compartment, the combination with a horizontal, tubular rail, and brackets fixed to the wall of the compartment in which said rail is mounted, the bracket at the open side of the compartment 60 being hollow to receive the adjacent end of the rail, of a tubular extension rail, a hinge for connecting said extension rail to said hollow bracket, said fixed and extension rails being provided on their under sides with slots 65 and the hinge and said hollow bracket being

similarly slotted to provide a continuous slot from the inner end of the fixed rail to the outer end of the extension rail, a carriage having parts extending through the slots which have bearing in the interior of the tubular rail, and means for supporting the outer end of the extension rail in a horizontal position.

9. In a wardrobe or compartment, the combination with a fixed horizontal rail 75 therein, of a hinged extension rail adapted to occupy and be sustained in a horizontal position in alinement with the fixed rail, a hinge for the extension rail comprising lugs or ears on the extension rail, hinged pins extending 80 through lugs or ears and into a part stationary with the fixed rail, one of said lugs being provided with an opening, and the said fixed part with a registering opening, a pin adapted to enter said registering opening when the 85 extension rail occupies a horizontal position, and a hanger sustaining carriage movable on said rails.

10. The combination with a receiving compartment, of a fixed, horizontal rail 90 therein, an extension rail connected therewith and adapted to be folded into the compartment perpendicular to the fixed rail when not in use, a hanger sustaining carriage supported by and movable on said fixed and 95 extension rails, and a supporting standard hinged to the outer end of said extension rail and constructed to be folded inside the compartment parallel with the extension rail.

11. The combination with a receiving 100 compartment, of a fixed, horizontal rail therein, an extension rail hinged directly to the fixed rail and adapted to be folded when not in use into the compartment, a hanger sustaining carriage supported by and movable on said fixed and extension rails, and a standard supporting the outer end of the extension rail and having telescopic connection therewith.

12. The combination with a receiving 110 compartment, of a fixed horizontal rail therein, an extension rail hinged directly to the fixed rail and adapted to be folded when not in use into the compartment, a hanger sustaining carriage supported by and movable on said fixed and extension rails, and a supporting standard hinged to the outer end of the extension rail and having telescopic connection therewith.

13. The combination with a receiving compartment, of a fixed, horizontal rail therein, an extension rail connected therewith and adapted to be folded, when not in use, into the compartment, a hanger sustaining carriage supported by and movable on said fixed 125 and extension rails, a supporting standard hinged to the outer end of the extension rail, the said latter rail being tubular to receive said standard and its hinge, and means preventing rotation of said standard and its 130

sliding hinge relatively to the tubular extension rail.

14. The combination with a receiving compartment, of a fixed horizontal rail therein, an extension rail connected therewith and adapted to be folded, when not in use, into the compartment, a hanger sustaining carriage supported by and movable on said fixed and extension rails, and a supporting standard hinged to the outer end of the extension rail, the said latter rail being tubular to receive said standard and its hinge, said extension rail being longitudinally slotted and one of the hinge members being provided with a lug adapted to slidingly engage said slot.

15. The combination with a receiving compartment, of a fixed rail therein, an extension rail hinged to the fixed rail, a hanger supporting carriage supported by and movable on the fixed and extension rails, a supporting standard hinged to the outer end of said extension rail, said standard and its hinge having telescopic connection with the extension rail.

25 16. The combination with a receiving compartment, of a fixed rail therein, a hinged extension rail, and a supporting standard hinged to the outer end of the extension rail, said extension rail being made hollow, the hinge therefor comprising a block sliding longitudinally in the hollow extension rail, and a member on the standard having hinged connection with said block.

17. The combination with a receiving compartment, of a fixed rail therein, a hinged extension rail, and a supporting standard hinged to the outer end of the extension rail, said extension rail being made hollow and longitudinally slotted, the hinge therefor comprising a block sliding longitudinally in the hollow extension rail, a hinged member on the standard having hinged connection with said block, and a lug on said hinge-block engaging the slot in the extension rail.

45 18. The combination with a receiving compartment, of a fixed rail therein, a hinged extension rail, and a supporting standard hinged to the outer end of the extension rail, said extension rail being made hollow, the hinge therefor comprising a block sliding longitudinally in the hollow extension rail, a member on the standard having hinged connection with said block, and a stop in the outer end of said extension rail for preventing complete withdrawal of said sliding block therefrom.

19. The combination with a receiving compartment, of a fixed rail therein, a hinged extension rail and a supporting standard hinged to the outer end of the extension rail, said extension rail being made hollow, the hinge therefor comprising a block sliding longitudinally in the hollow extension rail, a member on the standard having hinged connection with said block, a stop in the outer end

of said extension rail for preventing complete withdrawal of said sliding block therefrom, and interlocking connections between said stop and sliding block preventing angular displacement of the block in said tubular extension rail.

20. The combination with a receiving compartment, of a fixed rail therein, a hinged extension rail, a supporting standard hinged to the outer end of the extension rail, said extension rail being made hollow, the hinge comprising a block sliding longitudinally in said extension rail and provided with a hinge lug, a hinge lug on the upper end of the standard and a pin extending through registering apertures in said lugs, and a stop for limiting the outward movement of the block in said tubular extension rail, the upper end of the standard engaging the outer end of the extension rail in a manner to closely confine said stop between the standard and said sliding block.

21. The combination with a receiving compartment, of a fixed rail therein, an extension rail connected therewith and adapted to be folded into said compartment, a hanger supporting carriage movable on said fixed and extension rails, a standard for supporting the outer end of the extension rail and a foot or base for said supporting standard having vertically adjustable connections with said standard.

22. The combination with a receiving compartment, of a fixed rail therein, an extension rail hinged to the fixed rail, a hanger supporting carriage supported by and movable on the fixed and extension rails, a supporting standard hinged to the outer end of said extension rail, said standard and its hinge having telescopic connection with the extension rail, and a foot or base for the supporting standard having vertical adjustment therewith.

23. The combination with a receiving compartment, of a fixed rail therein, an extension rail hinged to the fixed rail, a hanger supporting carriage supported by and movable on the fixed and extension rails, a supporting standard hinged to the outer end of said extension rail, said standard and its hinge having telescopic connection with the extension rail, a foot or base for said supporting standard embracing a shank that extends upwardly into the hollow standard and a pin on the shank adapted to releasably engage a notch in said standard.

24. The combination with a receiving compartment and a door for closing same, of a fixed rail in said compartment, an extension rail hinged thereto, a carriage movable on said rails, said extension rail being constructed and designed to be contained in said compartment when not in use, and means whereby said extension rail is supported in horizontal extension of the fixed rail, includ-

6
ing a locking pin engaged with the hinge of
said extension rail, said fixed and extension
rails being formed with tracks or ways which
are disposed in alinement when the exten-

5 sion rail is in its horizontal position.

In testimony, that we claim the foregoing
as our invention we affix our signatures in the

presence of two witnesses, this 4th day of
August A. D. 1906.
